PROCESS FOR PYROLYTIC CONVERSION OF PETROLEUM OILS

Filed June 29, 1927

FIG.-2

FIG.-3

FIG.-1
Inventor
FRANK A. HOWARD

By his Attorneys *A. Howard*

UNITED STATES PATENT OFFICE

FRANK A. HOWARD, OF ELIZABETH, NEW JERSEY, ASSIGNOR TO STANDARD OIL DEVELOPMENT COMPANY, A CORPORATION OF DELAWARE

PROCESS FOR PYROLYtic CONVERSION OF PETROLEUM OILS

Application filed June 29, 1927. Serial No. 202,191.

This invention relates to the cracking of petroleum oils in equipment comprising a heating conduit discharging into a thermally insulated digesting chamber or soaking drum.

I have found that the conversion efficiency of such systems may be materially increased and the formation of troublesome carbonaceous deposits in the drum decreased by maintaining a local circulation in the drum.

The invention will be fully understood from the following description, read in connection with the accompanying drawing, in which:

15 Fig. 1 is a diagrammatic vertical section through equipment suitable for carrying out my method, and;

Figs. 2 and 3 are views similar to Fig. 1 showing alternative forms of the equipment.

20 Reference numeral 1 in each figure designates a firebrick setting heated by any suitable means. Fresh oil is supplied through inlet pipe 2 to heating conduit 3, which consists preferably of a series of tubes joined

25 end to end by crossover connections to form a continuous circuit. Heating conduit 3 discharges through pipe 4 into digesting chamber or soaking drum 5 surrounded by thermal insulation 6. 7 is a line for the continuous withdrawal of the cracked product. A pressure control valve 7' is installed in this line. The cracked product is fractionated and condensed in any suitable way.

Referring particularly to Fig. 1 a pipe 8 35 communicates with the soaking drum 5 at a point near the top thereof. A pump 9 may be operated to continuously draw oil through pipe 8 into pipe 10, which in turn discharges into heating conduit 3.

40 Referring specifically to Fig. 2, a rotatable propeller 11 is attached to shaft 12, actuated by motor 13. 14 is a stuffing box through which shaft 12 enters the drum and 15 is a draft tube to cause the material propelled 45 to traverse a substantial part of the length of the drum to maintain the desired circulation.

Referring specifically to Fig. 3, a jet 16 is 50 arranged to discharge the heated material from conduit 3 into drum 5. 17 represents a

draft tube or pipe and 18 a Venturi throat which, however, may be dispensed with. This form of the invention is generally to be preferred.

The circulation of oil and/or oil vapor 55 in the drum is preferably continuous throughout the cracking period. Since methods of operating coil and drum installations of the type described are well known (except as to the local circulation in the drum), no 60 description of such methods is required here.

While I have described my invention in conjunction with certain specific forms of apparatus, it will be understood that it is not limited thereto but covers broadly any cracking system in which oils are caused to flow under pressure in a continuous stream through a heating zone in which they are heated to cracking temperature and are subsequently transferred to a soaking or digesting chamber in which the temperature is not raised and a positive local circulation of the 70 contents of the chamber is maintained.

What I claim is:

The improvement in cracking which comprises flowing a stream of the oil through an elongated narrow heating zone under conditions to give substantial cracking, then through a thermally insulated enlarged digestion zone in which the oil is held for a 80 relatively long time under cracking conditions, continuously abstracting oil from said digestion zone, uniting such abstracted oil with said stream in the heating zone at an intermediate point, heating the combined 85 stream, returning the same to the digestion zone, and continuously withdrawing all of the fluid products from the digestion zone in a single stream.

FRANK A. HOWARD. 90
